UNITED STATES PATENT OFFICE.

GEORGE D. CLARK AND DWIGHT G. CLARK, OF PLAINVILLE, CONNECTICUT.

DESIGN FOR A CASTER-FRAME.

SPECIFICATION forming part of Design No. 32,224, dated February 13, 1900.

Application filed December 30, 1899. Serial No. 742,173. Term of patent 7 years.

To all whom it may concern:

Be it known that we, GEORGE D. CLARK and DWIGHT G. CLARK, citizens of the United States, residing at Plainville, county of Hartford, State of Connecticut, have invented and produced a certain new and original Design for a Caster-Frame, of which the following is a full, clear, and exact description.

Our invention relates to a new and original design for a caster-frame.

In the accompanying drawings, Figure 1 is a side elevation. Fig. 2 is a front elevation looking in the direction of the arrows. Fig. 3 is a plan view.

The leading features of our design are found in the saddle portion of the caster-frame.

A A' are substantially parallel cheek-pieces

which are united by an arched portion B, the lower line of which is bowed upwardly. The parts A A' and B form the saddle. As seen ²⁰ in Fig. 3, the plan view of the arched portion B is of substantially rectangular outline.

D is an upward extension from the arched portion B.

What we claim is—

The design for a caster-frame substantially as herein shown and described.

Signed at Plainville, Connecticut, this 6th day of December, 1899.

GEORGE D. CLARK.
DWIGHT G. CLARK.

Witnesses:

MARY G. CLARK,
J. SANFORD CORBAN.
